UNITED STATES PATENT OFFICE.

ROBERT H. KEATON, OF SAN FRANCISCO, CALIFORNIA.

DESIGN FOR AN AUTOMOBILE TIRE.

Application filed May 10, 1924. Serial No. 9,552. Term of patent 3½ years.

To all whom it may concern:

Be it known that I, ROBERT H. KEATON, a citizen of the United States, residing at the city and county of San Francisco, State of California, have invented a new, original, and ornamental Design for Automobile Tires, of which the following is a specification, reference being had to the accompanying drawing, forming part thereof.

The figure is a view in perspective, showing my new design, with parts broken away to more clearly disclose its sectional contour.

I claim:

The ornamental design for an automobile tire, substantially as shown.

ROBERT H. KEATON.
